United States Patent Office

Des. 186,961
Patented Dec. 29, 1959

186,961

METERING PUMP UNIT

Dennis L. Eidson, Barrington, Ill., assignor to Hills-McCanna Company, Chicago, Ill., a corporation of Illinois

Application October 30, 1956, Serial No. 43,590

Term of patent 14 years

(Cl. D65—1)

Fig. 1.

Fig. 2.

Fig. 3.

Fig. 4.

Fig. 1 is a side elevational view of a metering pump unit embodying the design of the present invention;

Fig. 2 is a top plan view thereof, and Figs. 3 and 4 are end elevational views of the pump unit taken from the left and right of Fig. 1 respectively.

I claim:

The ornamental design for a metering pump unit, substantially as shown.
